CLAIM

The ornamental design for a harmonica holder, as shown and described.

DESCRIPTION

FIG. 1 is a top, front perspective view of a harmonica holder showing our new design;

FIG. 2 is a top plan view thereof;

FIG. 3 is a bottom plan view thereof;

FIG. 4 is a front elevational view thereof, the rear elevational view being the mirror image thereof; and,

FIG. 5 is a side elevational view thereof, the opposite side elevational view being the mirror image thereof.
